(57) **CLAIM**

The ornamental design for a R/C vehicle chassis, as shown and described.

DESCRIPTION

FIG. 1 is a top perspective view of a R/C vehicle chassis, according to my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a bottom perspective view thereof, illustrating an exploded view of a motor replacement opening;

FIG. 10 is a bottom perspective view thereof, illustrating an open battery cover;

FIG. 11 is a bottom perspective view thereof, illustrating a closed battery cover; and,

FIG. 12 is a bottom perspective view thereof, illustrating an open battery cover.

The broken lines illustrate portions of the R/C vehicle chassis that form no part of the claimed design.
